ABSTRACT: Apparatus for treating razor blades wherein a stack of razor blades disposed in a holder is successively passed through a blade cleaning unit, a preheater, a spraying unit for depositing a thin coating of shaving facilitating material on the blade edges, a heating unit for curing said material, and a cooling unit. The blades are contained loosely in the blade holder while passing through the cleaning unit to permit them to be thoroughly cleaned and are thereafter clamped together in a compact stack for subsequent treatment. The cleaning unit includes a plurality of nozzles, the operation of which is in timed relationship with the conveyor so that only those nozzles which are opposite specific holder locations on the conveyor emit cleaning fluid.

HOLDER FOR RAZOR BLADES

This application is a division of copending application Ser. No. 403,693, filed Oct. 5, 1964, now U.S. Pat. No. 3,498,257, which is a continuation of application Ser. No. 331,080, filed Dec. 10, 1963, now abandoned, which was a continuation of application Ser. No. 30,265 filed May 19, 1960, now abandoned.

This invention relates to a razor blade holder for stably supporting a stack of razor blades so as to permit them to be subjected to various treatments as described in our above identified U.S. Pat. No. 3,498,257 the disclosure of which is incorporated herein by reference without removal.

An object of the invention is to provide a holder for a stack of razor blades adapted to be carried stably by conveyors and subjected to various manipulations while shielding the delicate blades edges from becoming damaged and yet maintaining the blades fully exposed for various types of treatments.

A more specific object is to provide a holder for holding a stack of blades loosely in a fully exposed position to permit them to be rifled while subjected to fluid cleaning sprays, and to be subsequently clamped together into a compact stack for edge treatments.

Other objects, features and advantages of the invention will be appreciated from the following description of a particular embodiment thereof together with a particular apparatus and process for treating blades disclosed in our U.S. Pat. No. 3,498,257 for which it is particularly advantageous, as illustrated in the drawing in which:

FIG. 1 is a plan view of a blade holder;

FIG. 2 is an elevational side view of the blade holder;

FIG. 3 is an end view of the blade holder as seen from the left of FIG. 2;

FIG. 4 is a sectional view of the blade holder taken on line 4-4 of FIG. 2;

FIG. 5 is an end view of the blade holder as seen from the right of FIG. 2;

FIG. 6 is a fragmentary view of the blade spindle of FIG. 2 holding a stack of double edged razor blades.

As shown in FIGS. 1 and 2 the blade holder 68 comprises a generally rectangular base 70, a vertically extending bracket 72 rigidly secured to the base near the rear end thereof and a blade supporting spindle 74 extending horizontally forwardly from the bracket centrally of and above the base 70. The bottom of the base 70 is provided with a transverse rectangular opening 79 and a forward recess 80 in the base 70 permit free circulation of air from beneath the holder and about the blades mounted on the spindle 74. The forward end of the spindle 74 is rounded off in elevation and is beveled to a dull edge to permit ease of insertion in the central slot of a stack of double edged razor blades. The spindle is provided with a plurality of apertures 82 arranged equidistantly in three straight rows parallel to the sides of the spindle and the rear end thereof is forked to provide a rearwardly extending cutout 83 to receive the central solid portion 84 between longitudinal slots 86 in the top and bottom of a blade clamping member 85. The forked end of the spindle is received within a vertical slot 87 in the front face of the bracket and is rigidly secured thereto as by a pair of dowel pins or rivets 88. The blade clamping member 85 is carried by a pair of vertically and transversely offset horizontal rods 90 and 91 slidably mounted in bores extending through the bracket 72 and rigidly secured to the clamping member. A clamping screw 89 extends through the bracket 72 in threaded engagement therewith and bears against the rear face of the clamping member 85 to move it forwardly. The clamping member 85 is biased rearwardly by springs 92 confined between heads 93 on the rods 90 and 91 and the bottom ends of recesses 94 formed in the rear face of the bracket 72. Vertical marginal flanges 95 extend forwardly from the front face of the blade clamping

member 85 for engaging the rearmost blade of the blade stack mounted on the spindle 74 inside the sharpened beveled edges thereof. The spindle 74 is so dimensioned in cross section that it will be received within the longitudinal slot in a double-edged razor blade without undue play either vertically or laterally. A forked blade retaining member 96 is slidably mounted on the spindle 74 and the rear face thereof is provided with a pair of rearwardly extending marginal flanges 97 spaced and arranged so as to engage the foremost blade of a blade stack mounted on the spindle, like the flanges 95 of the blade clamping member 85 engage the rearmost blade. An L-shaped locking member 98 is swingably mounted about a pivot pin 100 on the front face of the retaining member 96 and carries a locking pin 102 adapted to extend through one of the apertures 82 in the central row to lock the retaining member 96 in position on the spindle 74. A knurled finger grip 104 is secured to and extends forwardly from the locking member 98 which can be swung thereby to the dotted position wherein the retaining member 96 can be removed from the spindle 74 to permit either loading or unloading of blades. The base 70 is provided with a recess 106 in the rear end of for receiving pusher lugs or studs carried by the conveyor chains 22 and 44. To load the blades on the holder, the retaining member 96 is removed as described above and the clamping screw 89 is backed off permitting the clamping member 85 to be moved to the right by the return spring 92. A stack of the razor blades 108, FIG. 6, is now slid on the spindle 74 against the flanges 95 of the clamping member 85. The retaining member 96 is placed on the spindle 74 in front of the stack of razor blades and the locking pin 102 is caused to engage the nearest one of the apertures 82 that will leave at least a quarter of an inch between the retaining member 96 and the front end of the blade stack. This will permit the blades to flutter on the spindle under the impact of cleaning fluid spray and the drying air stream to thoroughly clean and dry the blades. The blades can be clamped together firmly during the blade coating steps of the process described in our above identified Patent 3,498,257 and to this end the clamping screw 89 is screwed inwardly thus displacing the clamping member 85 towards the retaining member 96 to apply pressure against the opposite ends of the blade stack. It should be noted that the sides of the base 70 extend laterally well outside of the edges of the blade so as to protect them against damage if the holder should hit up against some object. Having thus described our invention with particular reference to an illustrative embodiment thereof it will be obvious to those skilled in the art to which the invention pertains that various changes and modifications may be made therein without departing from the spirit and scope of our invention. We claim:

1. A blade holder for a stack of razor blades comprising a base, blade supporting means disposed in spaced relation to said base for supporting a plurality of razor blades in a stack with their cutting edges in parallel relation above and spaced from said base, first blade securing means for securing a stack of blades on said supporting means while permitting limited relative movement between individual blades in the stack, and second blade securing means cooperating with said first blade securing means and said supporting means for clamping said stack of blades together in a compact stack on said holder so that only the blade edges of intermediate blades are exposed.

2. A blade holder for a stack of razor blades comprising a base, blade supporting means disposed in spaced relation to said base for supporting a plurality of razor blades in a stack with their cutting edges in parallel relation above and spaced from said base such that air may flow freely between said supported stack of blades and said base, first blade securing means including an adjustable stop and a resiliently mounted stop for securing a stack of blades on said supporting means between said stops while permitting limited relative movement between individual blades in the stack, and blade clamping means cooperating with said resiliently mounted stop and said

supporting means for moving said resiliently mounted stop towards said adjustable stop for clamping said stack of blades firmly together in a compact stack on said holder so that only the blade edges of intermediate blades are exposed.

3. A blade holder for holding a stack of razor blades comprising a base including an upwardly extending bracket, a straight blade supporting spindle on said bracket extending substantially horizontally therefrom above and spaced from said base, said spindle terminating in a freely supported end and being dimensioned to be received within elongated apertures in the razor blades, and removable blade retaining means slidably supported on said blade supporting spindle including locking means engageable with said spindle for securing said retaining means selectively in a plurality of positions along said supporting spindle.

4. A blade holder for holding a stack of razor blades comprising a base including an upwardly extending bracket, a straight perforated blade supporting spindle on said bracket extending substantially horizontally therefrom above and

spaced from said base, said spindle terminating in a freely supported end and being dimensioned to be received within elongated apertures in the razor blades, and removable blade retaining means slidably supported on said blade supporting spindle including locking means cooperating with the perforations in said supporting spindle for securing said retaining means selectively in a plurality of positions therealong.

5. A blade holder for holding a plurality of razor blades in stack fashion comprising a base including upwardly extending bracket means, a straight blade supporting spindle extending from said bracket means and having a freely supported end, said spindle being spaced from said base and dimensioned to be received within apertures in the razor blades, removable blade retaining means slidable on said spindle including locking means for adjustably locking said retaining means on said spindle, and releasable blade clamping means between said retaining means and said bracket means and arranged to move along said spindle toward and away from said bracket.
